UNITED STATES PATENT OFFICE.

JOHN L. HARPER, OF SEATTLE, WASHINGTON.

JACK.

Application filed May 17, 1922, Serial No. 561,596. Renewed March 25, 1925.

To all whom it may concern:

Be it known that I, JOHN L. HARPER, a citizen of the United States, and a resident of Seattle, county of King, and State of Washington, have invented certain new and useful Improvements in Jacks, of which the following is a specification.

This invention relates to improvements in jacks, and particularly to jacks of that type especially desirable as an automobile, and truck accessory, and which embodies in its construction a cylinder and a cylinder piston, with means for forcing a liquid pressure medium from one into the other to effect a lifting action by the jack.

It is the principal object of this invention to provide a hydrostatic jack of the above character having an extendible pump which will permit easy operation of the device and which may be readily collapsed so that the jack may be stored in a minimum amount of space.

It is also an object of the invention to provide a jack of the above character where in there is a normally closed by-pass valve located within a return flow channel between the cylinder and cylinder piston and which may be moved to open position by certain manipulation of the pump rod connection so that the jack may be lowered without inconvenience to the operator and under the influence of the weight thereon.

Other objects of the invention reside in the details of construction of the extension handle and pump mechanism, the cylinder-piston and its valve mechanism and in the means for actuating the by-pass valve.

In accomplishing these and other objects of the invention, I have provided the improved details of construction, the preferred forms of which are illustrated in the accompanying drawings, wherein—

Figure 1 is a central, sectional view of a hydrostatic jack constructed in accordance with the present invention; showing the pump handle in extended position.

Figure 2 is a side view of the same, with the handle collapsed.

Figure 3 is a detail, sectional view, taken on the line 3—3 in Figure 1, and illustrating the connection of the handle with the jack head.

Figure 4 is a top view of the connection between the handle sections; showing the stop shoulders on the pivotally connected sections.

Figure 5 is a side view of a jack having a one-section handle.

Referring more in detail to the several views of the drawings—

1 designates the jack cylinder, and 2 a cylinder piston that is reciprocally slidable therein and wherein a liquid pressure medium such as oil, water or glycerine may be confined; the cylinder being provided at its lower end with an extended supporting base 3 and at its upper end is open and is exteriorly threaded to receive a clamping ring 4 thereon whereby a packing washer 5, disposed beneath the ring, may be tightened against the piston to preclude any possible leakage at the joint.

At its lower end, the cylinder-piston 2 is provided with a pump washer 6 which is held thereon by means of an overlying plate 7, and this, in turn, is tightened against the washer by means of nuts 8 and 9 that are threaded respectively onto the lower ends of tubes 10 and 11 that extend longitudinally through the piston and which open at their upper ends into channels 12 and 13 in a head 14 which is formed upon and closes the upper end of the cylinder-piston; the tube 10 in this instance opens at its lower end into the cylinder 1, while the tube 11 is closed at its lower end by the cap nut 9 and has an opening 15 into the piston, just above its bottom wall.

Both the channels 12 and 13 extend vertically within the head 14, and are connected at their upper ends by a horizontal channel 16 which leads into an annular channel 17 formed about the wall of a transverse bore 18 through the head. At the upper end of the channel 13 is a back check ball valve 20 whereby liquid pumped from the cylinder piston 2 through the tube 11 is prevented from returning, and located in the channel 16 is a ball check valve 21 whereby outward flow from cylinder 1 through tube 10 is prevented.

The channels 12 and 13 are also connected, below the check valves, by a horizontal channel 22 wherein there is located a spring pressed by-pass valve 23, which normally prevents flow from the channel 12 into 13. The valve 23 has a stem 24, one end of which extends from the head 14, as shown in Figure 1, and which may be pressed inwardly to unseat the valve to permit a flow of liquid from cylinder 1 into piston 2.

The handle for the device, which forms

the pump cylinder, consists of two hingedly connected, tubular sections 26 and 27; the section 26 being fitted at its inner end into a head 28 having a laterally extending, tapered shank 29 fitted within the transverse bore 18 of the head 14 and secured therein by means of a nut 30 threaded onto the end of the shank, as shown in Figure 3. The head 28 has a channel 31 communicating 10 with the tube 26 and extended into the shank and opening laterally into continuous communication with the annular channel 17 and head channel 16.

At its outer end, the handle section 26 has 15 an elbow 33 wherein is pivotally fitted the tapered shank 34 of an elbow 35 fixed to the inner end of the tube 27. The tubes 26 and 27 are kept in continuous communication at the joint by means of channels through the 20 elbows 33 and 35; the same being connected similarly as is the head 28 within the cylinder-piston head 14.

Slidably fitted within the tube 27 is a 25 pump rod or piston 38 provided at its outer end with a knob 39 whereby it may be actuated and about the outer end of the tube is an enlarged handle forming portion 40 and a packing ring 41 which prevents leakage.

30 It is desirable in this construction, in order that the jack may be properly positioned beneath the axle of a vehicle, that the handle forming sections can be extended in a straight line, as shown in Figure 1, and 35 retained substantially rigid. Then the operator may lift the jack from the outer end of the handle. In order to do this, yet at the same time allow the sections to be broken 40 downwardly, and moved to the position shown in Figure 2, I have provided lugs 42 and 43 respectively on the adjacent faces of the elbows 33 and 34 which will engage each other when the sections extend in the 45 same straight line.

45 In Figure 5, I have illustrated a jack having a single section handle which is of the same type of construction as the device of Figure 1 except that the handle section 27 is eliminated and the pump is applied within the section 26.

50 In order that one using the jack may, when it is desired, to lower the same, do this without necessitating his stooping over to press the valve stem 24, I have mounted a pin 50 within the head 28, see Figures 1 and 55 3, which is slidably transversely therein and which has head portions at its ends whereby it is retained from being displaced. When it is desired to lower the jack, this pin 50 is 60 shifted, to the dotted line position in Figure 3, so that when the handle section 26 is moved downwardly, as indicated in dotted lines in Figure 1, the head of the pin will bear against the valve stem 24 to press it inwardly and unseat the valve 23.

Assuming that the device is so constructed and assembled, it can be used in the following manner: The cylinder piston 2 is first lowered and is filled, by removing the plug 52 from a top opening 53 therein, see Figure 70 3, with a suitable fluid. The pump handle sections 26 and 27 are then extended, as shown in Figure 1, and by means of the handle, or otherwise, the jack is located beneath the object to be raised. Then by reciprocating the pump rod 38, liquid will be drawn from the piston through tube 11 and driven into cylinder 1 through tube 10 and this will cause the piston to be lifted, return 75 flow being prevented by the back check 80 valves 20 and 21.

When it is desired to lower the jack, the handle is broken downwardly so that the pin 50 can be engaged with the valve stem 24 to unseat valve 23 and allow a flow of the 85 liquid from the cylinder through tube 10, channel 22 and tube 11 into the cylinder-piston which will allow the latter to move downwardly accordingly as the quantity of oil in the cylinder is decreased.

90 It is readily apparent that jacks of this character can be used for all purposes and can be made in various sizes to suit the purposes for which they are intended.

95 It is further apparent that such jacks can be stored in a very small space, are easy to operate and by their use, a person is able to lift loads that cannot be lifted by use of the ordinary types of geared jacks.

Having thus described my invention, 100 what I claim as new therein and desire to secure by Letters-Patent, is:

1. A jack of the class described, comprising a base cylinder, a piston movable within the cylinder and extending therefrom, a pump tube pivotally connected with the piston, a piston operable within said tube whereby a liquid pressure medium may be pumped from within the piston into the cylinder, a by-pass valve within the upper end of the piston having a stem extending therefrom, and means movable with the pump tube adapted to engage with the said stem to open the valve and permit a return flow of the liquid from the cylinder into the piston.

110 2. A jack of the class described, comprising a base cylinder, a cylinder piston operable within the base cylinder and having a lifting head at its upper end, with channels therein having lower end connections opening respectively into the cylinder and cylinder piston and having upper end connections with a cross channel, a pump tube mounted pivotally at its inner end in said head and having communication with the said cross channel, a pump piston operable within the tube, and check valves in the channels whereby a fluid pressure medium may be forced, by opera- 115 120 125 130

tion of the pump, from the piston into the cylinder to lift the piston, a normally closed by-pass valve connecting the channels and having a stem extending from the head, and 5 means movable with the pump tube, engageable with the said stem to unseat the valve to allow a return flow from the cylinder into the piston.

3. A jack of the character described, comprising a base cylinder, a cylinder piston movable within the base cylinder with a lifting head at its upper end, having two vertical channels therein connected across their upper ends by a cross channel, tubes leading from the lower ends of said vertical channels, opening respectively into the cylinder and cylinder piston, a pump tube mounting having a laterally extended shank pivotally mounted in the lifting head for movement of the tube in a vertical plane, and providing continuous communication between the pump tube and cross channel, a pump piston in the said tube, back-check valves in the head channels whereby, upon 15 operation of the pump, a liquid pressure medium may be forced from the piston into

the cylinder, a normally closed by-pass valve connecting the vertical channels having a stem extending from the head, a pin mounted in the pump tube mounting movable to position to be engaged with the valve stem when the tube is moved downwardly to thereby unseat the valve to permit a return flow of the pressure medium into the pistons. 30

4. A device as set forth in claim 1, wherein the pump tube consists of a plurality of pivotally connected sections for movement in vertical planes to be folded against the cylinder and wherein the pump piston is 35 mounted within the outer end section.

5. A device as in claim 4, wherein the sections of the pump tube are provided with stop shoulders whereby their upward, pivotal movement at the joint is limited and the 40 sections may be retained against further movement when in a straight line but may be broken downwardly at the joint.

Signed at Seattle, Washington, this 12th day of May, 1922.

JOHN L. HARPER.
